UNITED STATES PATENT OFFICE.

FREDERICK ALBIN WEIGEL, OF JOHNNETTA, PENNSYLVANIA.

BURNING-KILN.

No. 861,410.

Specification of Letters Patent.

Patented July 30, 1907.

Application filed July 3, 1906. Serial No. 324,591.

To all whom it may concern:

Be it known that I, FREDERICK ALBIN WEIGEL, a citizen of the United States, residing at Johnetta, in the county of Armstrong and State of Pennsylvania, have invented certain new and useful Improvements 5 in Burning-Kilns; and I do declare the following to be a full, clear, and exact description of the invention, such as will enable others skilled in the art to which it appertains to make and use the same, reference being 10 had to the accompanying drawings, and to the letters and figures of reference marked thereon, which form a part of this specification.

My invention relates to a new and useful improvement in down draft kilns for the burning of brick, 15 sewer pipe, or any article formed from earth or clay.

The primary object of my invention is the construction of a kiln in which a regular heat may be obtained throughout the entire burning chamber, thus being able to burn the contents to a uniform hardness and 20 by means of the arrangement of flues and draft passages being able to deflect the heat to any desired point.

Another feature of my invention is the method of drawing off the heat from the burning chamber and effecting a gradual cooling off of the contents, also the 25 convenient and practical method of cleaning the kiln after each burning process.

In the accompanying drawings, in three sheets, forming a part of this specification, I have shown several detailed views of my invention, Figure 1 being a 30 longitudinal section on line 1—1 of Fig. 3. Fig. 2, Sheet 2, is a plan view showing draft flues leading to stack. Fig. 3, Sheet 3, is a cross sectional view on line 3—3 of Fig. 1. Fig. 4, Sheet 1, is a plan view of a section of the checker work flooring before the final layer 35 of brick is put on. Fig. 5, Sheet 3, is a similar view showing one-half complete with the final layer of bricks. Fig. 6, Sheet 2, is a modified form for connecting the circular draft passage with the stack.

Throughout the drawings the numeral 1 indicates 40 the structural work of what is familiarly known as a bee hive oven, or burning kiln. At stated intervals around the oven are arranged heating furnaces 2 and at one side, any convenient distance from the oven, is a draft stack 3.

Extending from side to side of the oven is an arched 45 passage-way 4 one end built abruptly against the side of the oven and the opposite end communicating with an air-well, or man-hole 5. Communicating with this passage-way 4, which it enters at right angles midway 50 between the ends thereof, is a flue 6 leading to the draft stack 3, and located in this flue is a damper 6'. Through the top of the arched passage-way 4 at stated intervals are arranged a plurality of openings 7—7.

Built at right angles with the arched passage-way 4 55 between the openings 7—7 and parallel with the flue 6, are the solid brick walls 8—8, Fig. 3, the ends thereof

ending a short distance from the wall of the oven, shown by dotted line in Fig. 2, leaving a circular passage-way 9.

The floor of each air space 10 formed between these 60 walls 8, is inclined from the circular passage-way 9 to where it communicates with the openings 7—7 formed in the arched passage-way 4, all except the central passage-way above the draft flue 6, which has a flat floor. The object of having these sloping floors is to 65 facilitate the cleaning of the oven, as the scale from the burning brick and sand used in setting layers of brick will sift through the floor into the passage-ways 10 and can readily be drawn into the arched passage-way 4 and from there hauled away.

The walls 8—8, before referred to, are built to a pre-determined and uniform height and upon these walls, and at right angles therewith, are courses of brick 11—11; leaving air spaces between each course. Upon these courses of brick, and running at right angles therewith, is the floor 12, which consists of a series of brick laid in strips; leaving a space between each two strips.

A dividing wall 13 separates the ends of the circular passage-way 9, and each end of said passage-way communicates with an opening 14 into the flue 6. Located 80 near each end of each passage-way 9 are the dampers 15—15. As a modified form of construction, the ends of this circular passage-way 9 may be led directly into the stack, shown in Fig. 6.

Arranged in the walls of the oven at each side of the 85 furnace 2, and adjacent thereto, are air passages 16 and 17 to prevent buckling or bulging of the walls of the oven; the passage-way 17 communicating with the interior of the oven.

One or more doors 18 are arranged through the wall 90 of the oven for filling and removing brick.

In the operation of my improved burning kiln, the green brick, or other clay material, is hauled into the oven through the door 18 and piled upon the floor 12 in a well known manner. The heat from the furnaces 2 95 entering the oven is drawn down through this green material and upon reaching the floor 12 it escapes through the space between the strips of brick, and is then deflected to the right and left, passes down between the supporting columns 11—11, thence into the 100 passage-way 10 between the walls 8—8, and is then drawn into the arched passage-way 4 through the openings 7—7 and from there into the flues 6; where it escapes out of the stack 3. It being a well known fact that atmospheric conditions have a great deal to do 105 with the burning of brick and that often times one side of the kiln will burn faster than the other. I have provided a means whereby a portion of the heat in the kiln can be drawn to either side and thus by equalizing the same, cause a more even burning of the green 110 material. This particular feature that I have provided consists in the circular passage-way 9, which

- acts as an auxiliary flue in accomplishing the above result. As an example we will suppose that owing to certain atmospheric conditions one side of the kiln is discovered to be hotter than the other, all that is required is for the man in charge to raise the damper 15 in the end of the passage-way 9 at whatever side of the kiln he desires to draw the heat. A portion of the heat, which ordinarily will rush toward the center of the kiln where the draft is strongest, will thus be deflected to whatever side the operator desires and where the burning has been slowest heretofore. In this manner the distribution of heat in the kiln can be equalized to overcome any change in the atmospheric conditions.
- 15 In the cooling off process necessary before removing the bricks from the kiln, the ports 19 formed through the roof of the kiln are opened, thus admitting cold air to the burning chamber. Cold air will also be admitted through the passage-ways 17 formed in the wall 20 of the kiln, and as an additional means for furnishing cold air to assist in carrying off the heated atmosphere in the kiln, I have provided the air well 5 which communicates with the passage-way 4. In this manner a sufficient volume of cold air can be drawn into the 25 kiln to insure the rapid and efficient cooling off of the burned material. The air well 5 also acts as a man-hole in obtaining access to the passage way 4 when it becomes necessary to clean the kiln of the scale and sand; but is kept covered during the burning process.
- 30 An additional air well can be provided at the opposite end of the passage way 4 in case the conditions and nature of the construction would warrant the same being done.
- Other minor changes in the detailed form of construction may also be made without in any manner changing 35 or departing from my original idea.
- Having therefore fully described and shown my invention, what I claim as new, and desire to secure by Letters Patent, is:
- 40 1. In a device of the character described, a suitable burning kiln; a covered passage-way extending from side to side of the kiln; means, communicating with said passage-way, for drawing cold air into the kiln and for cleaning said kiln; a draft flue intersecting said passage-way and extending to a draft stack; a damper in said flue;
- 45

and a plurality of openings formed in said passage-way; as, and for, the purpose set forth.

2. In a device of the character described, a suitable burning kiln; a covered passage-way extending from side to side of the kiln and communicating with an air well; 50 a draft flue intersecting said passage-way and extending to a draft stack; a damper in said flue; a plurality of openings formed in said passage-way; a plurality of supporting walls or arches extending across at right angles with the covered passage-way and between the openings formed therein; and air spaces between each two walls communicating with the openings through the covered passage-way; as, and for, the purpose set forth.

3. In a device of the character described, a suitable burning kiln; a covered passage-way extending from side to side of the kiln and communicating with an air well; 60 a draft flue intersecting said passage-way and extending to a draft stack; a damper in said flue; a plurality of openings formed in said passage-way; a plurality of supporting walls extending across at right angles with the covered passage-way and between the openings formed therein; air spaces between each two walls communicating with the openings through the passage-way, the bottoms of which incline toward said passage-way; and a circular auxiliary flue extending around the kiln, communicating 70 with each air space and draft flue, the ends of said auxiliary flue being separated by a dividing wall and having damper means for regulating the draft therethrough; as, and for, the purpose set forth.

4. In a device of the character described, a suitable 75 burning kiln; a covered passage-way extending from side to side of the kiln and communicating with an air well; a draft flue intersecting said passage-way and extending to a draft stack; a damper in said flue; a plurality of 80 openings formed in said passage-way; a plurality of supporting walls extending across at right angles with the covered passage-way and between the openings formed therein; air spaces between each two walls communicating with the openings through the passage-way, the bottoms of which incline toward said passage-way; a circular auxiliary flue extending around the kiln communicating with each air space and draft flue, the ends of said auxiliary flue being separated by a dividing wall and having damper 85 means for regulating the draft therethrough; courses of brick resting on the parallel walls and supporting a 90 checker work flooring; and a plurality of air passages formed in the wall of the kiln; as, and for, the purpose set forth.

In testimony whereof, I affix my signature, in presence of two witnesses.

FREDERICK ALBIN WEIGEL.
